UNITED STATES PATENT OFFICE.

EDWIN P. WANNER, OF NEW YORK, N. Y.

BALUSTER FOR SEATING APPLIANCES.

1,235,263.

Specification of Letters Patent. Patented July 31, 1917.

Application filed August 24, 1914. Serial No. 858,295.

To all whom it may concern:

Be it known that I, EDWIN P. WANNER, a citizen of the United States, residing at New York city, in the county of New York and State of New York, have invented certain new and useful Improvements in Balusters for Seating Appliances, of which the following is a specification.

This invention relates to chairs and particularly to chairs of the kind having in the backs thereof a supporting member variously termed a "banister," "baluster" or "splat." This member usually comprises an upright portion and a cross-bar or rung into which the lower end of the upright portion is doweled, the upper end of the upright portion and the ends of the cross-bar being doweled into the main or arched part of the chair-back. The two parts—upright and cross-bar—are joined by glue or otherwise, but the joint is weak on account of the dowel and frequently breaks or loosens. My object is to provide a banister, baluster or splat that will be peculiarly stronger and less expensive to manufacture than the old construction because its upright and cross-bar or rung are integral and that will furthermore preserve in the chair a certain grace and appearance of strength and durability that exist only when the individuality of the upright and cross-bar is retained.

A further object of the invention is to provide a caned furniture element of the kind whose reverse side is more or less exposed to view, such as a caned banister, with a novel means for obscuring the caning loops at the back that will improve the appearance of the caned part and simplify the finishing treating thus involved.

Referring to the accompanying drawing in which the invention is fully illustrated,

Figure 1 is a perspective view of a chair provided with the improved banister;

Fig. 2 is a rear elevation of the improved banister;

Figs. 3 and 4 are fragmentary sectional views of the banister on the lines *x* and *y* of Fig. 1; and,

Fig. 5 is a view illustrating modifications of the means, shown in Figs. 3 and 4, for obscuring the caning loops at the back of the banister.

In said drawings *a* is the arched frame or main portion of the back of a chair and *b* the improved banister, the same including the plate-like upright member *c*, which is

doweled into the top of the frame *a*, and the cross-bar *d* from which the upright member *c* rises and which has its ends doweled into the sides *a* of the frame.

The improved banister is composed of a number of layers *e* of sheet material, preferably wood, in which case the grain of adjacent layers is crossed, each layer being continuous or integral through the entire area in front or rear elevation of the banister, that is, inclusive of its upright *c* and cross-bar *d*.

For the part of the banister comprehending only the cross-bar *d*, there are at one face of the banister—preferably the front face—other layers *f* of sheet material, likewise preferably of wood and, if so, having the grain thereof crossed.

It will be obvious that a banister so constructed is exceedingly strong and durable, especially since the parts *c* and *d* are not jointed together but are integral with each other. Further, that there is preserved in the structure a certain appearance of individuality in the parts *c* and *d*, that is, they retain the appearance of being separately formed and of the cross-bar, by virtue of its greater thickness, being peculiarly adapted for its function as a substantial brace connecting the two sides or upright portions of the frame *a*.

The shape of the banister as seen in front elevation may vary in accordance with any chosen designs.

The banister shown in the drawings is one which is caned, as at *g*, the caning being placed at the front face of the banister and secured along its margin by loops or lacings *h*, which appear inset at the back of the banister on account of a groove *i* formed in said back along the line of the loops or lacings. In an article such as a chair banister whose back is frequently quite as conspicuous as the front thereof, it is desired to conceal the groove *i* and loops *h* and thus impart a finish to the work. This is usually accomplished by driving an insert strip into the groove and then planing its exposed surface flush with the grooved surface. It requires great care and skill to fit such an insert strip neatly, and the completed work seldom appears to good advantage. According to my invention I secure, by means of brads *j* or otherwise, a flexible covering strip *k* over and along the groove. This may be made in sections, as shown in Fig. 2. Outwardly, it

has the appearance of being half-round in cross-section. On the inner side thereof I preferably provide a tongue *l* to fit in the groove and retain the strip against displacement; but this may be omitted as shown at the left in Fig. 5. Or the strip may be formed round in cross-section, as shown at *m*, right of Fig. 5, and of somewhat greater diameter than the width of the groove, so that when secured in place it will be wedged into the groove.

Besides imparting to the back of the banister a much handsomer finish than is imparted by the usual insert strip, my improved strip can obviously be applied much more quickly and without the exercise of any special skill.

Having thus fully described my invention, what I claim as new and desire to secure by

20 Letters Patent is:—

1. A banister for seating appliances comprising an upright plate-like member and a cross-bar member formed of layers of sheet material the part of each layer included in 25 the upright member being integral with that included in the cross-bar member, the cross-bar member being thicker than the upright member.

2. A banister for seating appliances com-

prising an upright plate-like member and a cross-bar member formed of layers of wood having the grain thereof crossed, the part of each layer included in the upright member being integral with that included in the cross-bar member, and the cross-bar member having an additional layer or layers at one side thereof and being thus thicker than the upright member.

3. As an article of manufacture, a caned furniture element having a groove at the reverse side thereof receiving, inset, the caning loops, and a flexible strip wider than and secured over and concealing the groove and having a longitudinal portion on its inner side fitting the latter.

4. As an article of manufacture, a caned furniture element having a groove at the reverse side thereof receiving, inset, the caning loops, and a flexible covering strip in cross-section of substantially round contour 50 and greater diameter than the width of the groove and held engaged in said groove.

In testimony whereof I affix my signature in presence of two witnesses.

EDWIN P. WANNER.
